UNITED STATES PATENT OFFICE.

JESSE CANBY MORGAN, OF NEW YORK, N. Y.

DESIGN FOR A HANDLE FOR SHAVING-BRUSHES.

46,316.

Specification for Design.

Patented Aug. 25, 1914.

Application filed April 1, 1914. Serial No. 828,913. Term of patent 14 years.

To all whom it may concern:

Be it known that I, JESSE CANBY MORGAN, a citizen of the United States, residing in the city, county, and State of New York, have invented a new, original, and ornamental Design for a Handle of a Shaving-Brush, of which the following is a specification, reference being had to the accompanying drawing, forming part thereof.

The figure is a perspective view of a handle for a shaving brush, showing my new design.

I claim—

The ornamental design for the handle of a shaving brush, as shown.

JESSE CANBY MORGAN.
